UNITED STATES PATENT OFFICE.

CHARLES T. GROSJEAN, OF NEW YORK, N. Y., ASSIGNOR TO TIFFANY & CO., OF SAME PLACE.

DESIGN FOR A HAT OR CLOTHES BRUSH.

SPECIFICATION forming part of Design No. 17,404, dated June 21, 1887.

Application filed March 18, 1887. Serial No. 231,449. Term of patent 7 years.

To all whom it may concern:

Be it known that I, CHARLES T. GROSJEAN, a citizen of the United States, and a resident of New York city, in the county and State of New York, have invented and produced a new and original Design for Hat or Clothes Brushes, of which the following is a specification, reference being had to the accompanying drawings, forming part thereof.

10 Figure 1 is a top or plan view of my newly designed hat or cloth brush. Fig. 2 is a side view of the same, and Fig. 3 is an end view of the same. Figs. 1^a, 1^b, 1^c, and 1^d are sectional views on the lines *a a*, *b b*, *c c*, and *d d* of Fig. 15 1, respectively.

15 My design consists in the shape or configuration of the brush so far as it relates to the outline or exterior curve of the body of the brush, as that is shown in a top or plan view.

20 The present design differs essentially in its character and effect from any design based upon the oval, the elliptical, or the rectangular.

The design consists in the outline of the brush, as shown in Fig. 1. The side lines of 25 the brush are long, compared with the top and bottom lines, and are curved very slightly both at their middle portions and during the greater

part of their lengths; but at their ends the curve is increased or sharpened, so as to meet the curving ends of the top and bottom lines. 30 The top line of the brush is also curved slightly and delicately, and the bottom line is formed substantially as the top line.

This design gives a peculiar and subtle richness and fullness to the appearance of the 35 brush, such as cannot be obtained by any variety of oval or elliptical forms, and yet avoids the stiffness and abruptness of any rectangular form. The design combines, therefore, the completeness of the rectangular form with a 40 gracefulness and beauty superior to the oval or elliptical, and produces an artistic motive or life distinct from anything hitherto known.

What I claim as new, and desire to secure by Letters Patent, is— 45

The design for hat or cloth brushes, substantially as shown and described, consisting of the outline of the body having its sides and its ends curved but slightly, with sharp curves at the corners.

CHARLES T. GROSJEAN.
